UNITED STATES PATENT OFFICE.

JOHN W. LUCAS, OF LOS ANGELES, CALIFORNIA.

WATER COOLER AND REFRIGERATOR.

Application filed January 19, 1923. Serial No. 613,657.

To all whom it may concern:

Be it known that I, JOHN W. LUCAS, a citizen of the United States, residing at Los Angeles, in the county of Los Angeles and 5 State of California, have invented new and useful Improvements in Water Coolers and Refrigerators, of which the following is a specification.

This invention relates to water coolers 10 and refrigerators, and has for its object to provide a built-in cooler and refrigerating apparatus, and more particularly to provide a built-in refrigerator which may be built concurrently with the construction of a 15 dwelling or other building, or which may be readily erected at any time and which is preferably constructed of a heat resistive material.

An object of the invention is to provide a 20 water cooler and refrigerator forming substantially an ice chamber and refrigerating chambers through which domestic water service pipes may be extended and which includes a chamber for receiving ice which is 25 adapted to be disposed directly in contact with the water service pipes so as to reduce the temperature of the water passing therethrough. Another object is to provide a 30 sanitary refrigerating apparatus having drain connections leading to a suitable point of disposal, preferably to the outlet sewer pipe system, and provided also with air venting means leading from the refrigerating food chambers.

Other objects and advantages will be made 35 manifest in the following specification of an embodiment of the invention illustrated in the accompanying drawings, wherein—

Figure 1 is a side elevation and partial 40 section showing a fragment of a building with which the improved refrigerator and water cooler is combined.

Fig. 2 is a horizontal plan and section.

Fig. 3 is a detail sectional view of the 45 vent or air outlet.

The present invention is shown as combined with a wall 2 of any building, as for instance a dwelling, the wall being provided with a built-in refrigerating structure preferably having walls 3 and 4 of concrete, 50 preferably used because of its heat resisting characteristics. The cooling structure may be, and preferably is, extending outwardly from the wall 2 of the building, and has interior partitions 5 dividing the structure 55 into a central ice chamber 6 and lateral cool-

ing chambers 7-7. The several chambers have respective doors 8-8 at the inner sides and are shown as arranged in the plane of the inside face of the wall, this being rendered possible by the outward projection of the refrigerating structure.

The walls 5 extend upwardly a suitable distance and the top of the refrigerating structure is provided with a convergent 65 dome 10 into which the cooling chambers 7, for food, will all open at the top. The dome is provided with any suitable hood 11 from which may be extended upwardly a vent pipe 12 provided with a cap 13. The cap is 70 designed to shed water and its lower edge is spaced from the outlet end of the vent pipe 12 to provide for circulation, and means are provided for preventing the entrance of insects, such means being shown as a screen 75 14 of suitable mesh.

The water cooling apparatus is shown as consisting of a cooled water pipe 15 leading from the service pipe 16 and extending into the ice chamber. The bottom 80 of the chamber is provided with a suitable number of lengths or coils of pipe 15' receiving water from the branch 15, and these coils are also extended up into the side walls of the ice chamber as indicated at 15^a. The 85 water coils 15' and 15^a are shown as embedded in the cement bottom and walls of the refrigerator, and an outlet pipe 15^b is extended, as for instance, into a position over a sink S arranged within the building. 90

From this it will be seen that so long as ice is supplied to the ice chamber, the water coils 15' and 15^a will be chilled and cold water may be drawn from the valve at the cold water pipe 15^b.

Constant drainage is provided from the ice chamber as by means of a drain pipe 18 leading from the bottom thereof and having a loop and connecting to the sewer pipe P.

It will be seen that I have provided an extremely practicable, not expensive, and also a sanitary form of combined water cooler and refrigerator having provision for draining of the water from the melted ice, 105 and also providing for ample ventilation of the chambers of the refrigerator.

Further embodiments, modifications and variations may be resorted to within the spirit of the invention as here claimed.

What is claimed is:

1. A built-in refrigerator structure in-

cluding a housing having within the same an ice chamber provided with means for access and being closed at the top, bottom, sides and front so as to form a substantially 5 air tight ice chamber, food spaces at the sides of the enclosed ice chamber in the housing and being provided with access doors, the upper part of the housing forming a ventilating space above the top of 10 the ice chamber, the said ventilating space being in communication with the said food spaces.

2. A water cooling and refrigerating construction comprising the combination with a 15 building wall having a suitable opening, of a concrete floor mounted in the opening and extending outwardly, concrete side walls mounted in the opening and extending outwardly and upwardly from the floor, a concrete outer wall connecting the side walls and the floor, concrete partitions extending upwardly from the floor and joined with the outer wall, thus forming three chambers, a concrete cover for the central chamber, water cooling coils partly imbedded in 20 the concrete work and adapted to be connected to a source of water supply and to a discharge faucet the central chamber be-

ing substantially air-tight, and a concrete dome covering all three chambers, there being doors leading into each chamber from the inner side, the concrete dome forming a ventilating chamber, such chamber being in communication with the side chambers. 30

3. A refrigerator construction comprising in combination a building having an outside wall, a refrigerator extending outwardly therefrom and built in said wall, the refrigerator having bottom, side and back walls, formed imperforate, an ice chamber 40 contained in the refrigerator having a closed top and a door inside the building for the insertion of ice, there being cooling chambers on each side of the ice chamber, doors on the cooling chambers into the building, the cooling chambers being open at the top, a roof covering extending upwardly from the sides and back of the refrigerator structure and an air vent at the top of the roof structure on the outside of the building, said 45 roof structure forming a ventilation chamber above the cooling chambers.

In testimony whereof I have signed my name to this specification.

JOHN W. LUCAS.
